UNITED STATES PATENT OFFICE.

JOHN T. CLARK, OF NEW YORK, N. Y.

DEVICE FOR HANDLING FREIGHT IN PACKAGES.

1,109,964.

Specification of Letters Patent.

Patented Sept. 8, 1914.

Original application filed August 9, 1910, Serial No. 576,353. Divided and this application filed October 21, 1911. Serial No. 655,882.

To all whom it may concern:

Be it known that I, JOHN T. CLARK, a citizen of the United States, residing in the city of New York, borough of Manhattan, county and State of New York, have invented a certain new and useful Device for Handling Freight in Packages, of which the following is a specification.

This invention is a sling for handling merchandise contained in barrels, and similar packages, wherein the barrels are suspended in such manner that they cannot become disengaged from the sling during the operation of hoisting them.

15 The invention of this application is a division of a prior application filed by me on August 9th, 1910, Serial No. 576,353.

The invention embodies two rigid load-engaging members each provided with two 20 hooks adapted to engage separately with the two barrels, or other packages, to be hoisted, and a single flexible connection engaging loosely with said load-engaging members, said flexible connection being adapted to exert strain uniformly on the load-engaging members in such manner as to draw them 25 firmly into engagement with the components of the divided load.

Other features of the invention, and the 30 advantages thereof, will appear in the course of the following detailed description taken in connection with the drawings.

In the accompanying drawings, I have 35 illustrated one practical embodiment of the invention, but the construction shown therein is to be understood as illustrative, only, and not as defining the limits of the invention.

Figure 1 is a perspective view of a sling 40 for hoisting barrels in accordance with this invention. Fig. 2 is a side view illustrating the positions of the parts when hoisting, and Fig. 3 is a detail front view of one of the load-engaging members.

45 A, B designate the load-engaging members and C the flexible connection, the said parts comprising the sling of this invention. Each load-engaging member is preferably triangular in form, and is composed of 50 metal, preferably bar or rod metal, the same being bent to form an eye or ring d at the upper middle part of the member. From this ring or eye, the arms of the member diverge in a downward direction, each arm 55 being provided with a hook or claw e. As

shown, the lower part of each arm is widened and bent outwardly and then upwardly, so that the hook or claw is positioned on one side of the arm and faces in an upward direction. The claw shown is 60 wider than the arm and is provided with upwardly pointing teeth, whereby the claw is adapted to so firmly engage with a barrel, at the chime thereof, as to preclude slipping.

The flexible connection is composed, preferably, of a rope, cable, or the like. Said connection extends loosely through the eyes d of the two load members, the ends of said connection being united so that the connection is in the form of a loop.

70 My sling is used as follows: The two members are positioned at the respective ends of the two barrels X, Y to be hoisted, said members extending transversely to the barrels so that the hook at one end of each 75 member will engage with one barrel and the hook at the opposite end of the member engages with the other barrel. The members thus span or bridge the space between the barrels constituting the load, and said members extend upwardly from the load, at the ends thereof. The loop or connection C extends between the members so as to unite them, and when the load is suspended during the hoisting operation, said loop draws 80 upon the members so as to move them to the inclined positions shown in Fig. 2.

85 Preparatory to hoisting the load, the hook f of a fall block F is engaged with the loop C, and the load is raised or lowered by 90 the operation of a fall rope G, the latter being reeved through the fall block. The pull of the fall-block hook f is exerted centrally on the upper member of the loop C so as to result in the member assuming the triangular form shown in Figs. 1 and 2, and this flexible loop in turn imposes strain 95 uniformly on the two load-engaging members, whereby the claws are pulled into tight engagement with the barrels composing the 100 load and said barrels are caused, by the weight thereof when the load is suspended, to impinge against each other. The members are thus held into engagement with the 105 barrels so securely that the load cannot become accidentally dislodged from the sling when hoisting the load, but when the load is deposited upon a floor, dock, or other surface, and the strain is relaxed on the fall line, the claws of the members can be readily 110

disengaged from the barrels, or the members will themselves drop away from the barrels so as to become disengaged therefrom automatically.

5 The sling is simple and strong in construction, economical to manufacture, and easy and rapid of manipulation so as to connect it to, or detach it from, the barrels. The sling may be used in many places, such as the 10 hatchways of vessels and of stores and warehouses, and it affords a simple and efficient means for rapidly and economically handling freight in barrels, or analogous containers.

15 Having thus fully described the invention, what I claim as new, and desire to secure by Letters Patent is:—

1. In a sling of the class described, the combination of a plurality of rigid load-engaging members each having upwardly converging arms and provided at their lower ends with upwardly facing hooks or claws, said load-engaging members being positioned to span the space between two barrels of a load and the hooks or claws of each member being adapted for engagement with the respective barrels at the ends thereof, a single flexible loop loosely engaged with

the upper portions of said load-engaging members, and a fall line detachably connected to the upper part of the loop at a point between, and equi-distant from, the rigid load-engaging members. 30

2. In a sling of the class described, the combination of two substantially triangular load-engaging members each composed of rigid material and each provided at the upper part with an eye and at the lower parts thereof with upwardly pointing claws, a single flexible loop running loosely through 35 the eyes of the respective load-engaging members, said load-engaging members being positioned to span two barrels of a load, and a fall line connected with the loop so as to exert stress thereon between the load-engaging members so that the load-engaging members will draw the components of the load 40 into contact with each other. 45

In testimony whereof I have signed my name to this specification in the presence of 50 two subscribing witnesses.

JOHN T. CLARK.
